UNITED STATES PATENT OFFICE.

WILEY STAFFORD, OF JEFFRIS, LOUISIANA.

SAW-SET.

1,111,926.

Specification of Letters Patent. Patented Sept. 29, 1914.

Application filed September 27, 1913. Serial No. 792,184.

To all whom it may concern:

Be it known that I, WILEY STAFFORD, a citizen of the United States, residing at Jeffris, in the parish of Concordia and State of Louisiana, have invented certain new and useful Improvements in Saw-Sets, of which the following is a specification, reference being had to the accompanying drawings.

This invention comprehends certain new and useful improvements in saw sets and has for its primary object to provide a saw set which may be readily adjusted for setting the teeth at the desired inclinations.

Another object is to provide a saw set of this character, the punch and socket of which are adjustable longitudinally of the base member.

Another object is to provide a saw set of this nature, having a gage upon the adjustable socket and novel means for adjusting the latter longitudinally of the base member and securing said socket in adjusted position.

Another object is to generally improve and simplify the construction and operation of devices of this character and thereby increase the efficiency and commercial value of the same.

With the above and other objects in view, this invention consists in the certain novel details of construction, combination and arrangement of parts to be hereinafter more fully described, claimed and illustrated in the accompanying drawings, in which—

Figure 1, is an elevational view of my improved saw set. Fig. 2, is a top plan view of the same, a portion of the base member being broken away. Fig. 3, is a vertical longitudinal sectional view through the device, a portion of the base member being broken away and parts shown in elevation. Fig. 4, is a fragmentary cross sectional view on the line 4—4 of Fig. 2, showing the gage upon the socket member.

Referring more specifically to the drawings in which similar reference characters designate corresponding parts throughout the several views, 1 indicates the base member which has one end beveled upon its upper face, as shown at 2 and is provided with a transverse elongated slot 3 extending longitudinally of the same at the inner end of the beveled portion, as clearly shown in Fig. 3.

The adjustable socket 4 is bifurcated at its lower end to form the spaced parallel legs

5 for engagement upon opposite sides of the base member 1 and each leg 5 is provided with a circular opening 6, one of the openings being threaded to receive the threaded end 7 of the clamping screw 8 positioned through the openings in the legs and through the transverse slot 3 to draw the legs 5 against the opposite sides of the base member 1 and thus clamp the socket in adjusted position. The socket 4 is provided with a forwardly extended portion 9, the lower end of which is beveled and spaced above the upper face of the base member 1 and a vertical circular opening 10 is provided in the main and extended portions of the socket, the lower end of the main portion of the socket being closed while the semicircular opening 10' is formed in the lower end of the extended portion of the socket, said opening forming the lower end of the opening or bore 10, while the closed lower end of the main portion of the socket forms a surface 11, the purpose of which will presently appear.

A punch 12 is positioned within the bore 10 and has a reduced end 13 of semi-circular form in cross-section, thus providing the flattened inner face 14 for engagement with the surface 11 to prevent rotation of the punch when the reduced end 13 is disposed through the reduced semi-circular opening 10' in the lower end of the extended portion of the socket. A coil spring 15 is engaged around the punch 12 within the vertical opening of the bore 10 and serves to resiliently retain the punch in its uppermost position. It will be understood that a hammer or other suitable instrument is engaged with the projecting upper end of the punch 12 for forcing the reduced end 13 through the opening 10' into engagement with a saw tooth to set the same and that the spring 15 automatically returns the punch to its uppermost position after the same has been engaged with the saw tooth.

When the device is to be used for setting, the saw is placed in proper position upon the upper face of the base member 1 with a tooth engaged upon the inclined end 2 of the base member 1 and beneath the lower end of the punch 12, it being understood that the socket 4 has been properly adjusted and secured in adjusted position, the adjustment being indicated by the gage 16 upon the front face of the socket 4 and one of the legs 5, as clearly shown in Fig. 4.

From the foregoing, it will be apparent that this device may be readily adjusted for setting the saw teeth at various inclinations and will be highly efficient in use. Further, owing to the extremely simple construction and the small number of parts included in the device, the same may be readily and cheaply manufactured and should any of the parts become worn or broken they may be readily and cheaply replaced. It will also be apparent that while I have shown the preferred form of the device, minor changes in the details of construction may be made within the scope of the appended claims without departing from the spirit of my invention.

Having thus described my invention, what I claim is:—

1. A device of the class described comprising a base member, an angularly adjustable socket mounted upon said base member, said socket member having a vertical circular opening therein, a punch mounted for reciprocation in said opening, means for

resiliently retaining said punch in its uppermost position, and means for preventing rotation of said punch within said circular opening.

2. A device of the class described comprising a base member, an angularly adjustable socket mounted upon said base member, said socket being provided with a vertical opening therein having a lug formed in the lower end thereof, whereby the lower end of said opening is of semi-circular form, a plunger mounted in said opening and having a portion of its lower end cut away thereby forming a semi-circular lower extremity for reciprocation through the semi-circular lower end of the opening, and means for resiliently retaining the plunger in its uppermost position.

In testimony whereof I hereunto affix my signature in the presence of two witnesses.

WILEY STAFFORD.
